(57) **CLAIM**

The ornamental design for a fork with multi-tiered handle, as shown and described.

DESCRIPTION

FIG. 1 is a top view of a fork with multi-tiered handle showing my new design;
FIG. 2 is a left side view thereof;
FIG. 3 is a bottom view thereof;
FIG. 4 is a perspective view from above thereof; and,
FIG. 5 is a perspective view from below thereof.
The right side view is a mirror image of FIG. 2
The broken line portion of the figure drawing is included to show unclaimed subject matter only and forms no part of the claimed design.

1 Claim, 5 Drawing Sheets

FIG. 1

FIG. 2

FIG. 3
